SPRING CONNECTING MEANS

David M. Robinson, New Britain, Conn., assignor
to The Stanley Works, New Britain, Conn., a
corporation of Connecticut

Application October 11, 1949, Serial No. 120,698

3 Claims. (Cl. 267—73)

1

The present invention relates to spring attaching means and, more particularly, to a device for providing a connection to the end of a spiral spring which can be quickly installed and which is designed for use when the spring is to be put under tension.

The invention has particular utility in the overhead door art where counterbalancing of the door is accomplished by use of the spiral springs which are put under tension as the door is moved to closed position. In such installations, it generally is the practice to anchor one end of the spring on the door frame while the other end is secured to the door. Usually, it is necessary or at least desirable to have one of the spring connections adjustable to vary the spring tension.

It is an object of the present invention to provide a spring connection having particular advantage for use in overhead door installations. Included within this object is the aim of providing a connector of simple construction which can be installed or inserted with a minimum of effort, which will be economical to produce, which, despite its simplicity and ease of installation, will not be likely to slip or become disengaged and which will be sufficiently rugged to provide all the strength necessary and to withstand hard usage.

Other objects will be in part obvious and in part pointed out more in detail hereinafter.

The invention accordingly consists in the features of construction, combination of elements and arrangement of parts which will be exemplified in the construction hereafter set forth and the scope of the application of which will be indicated in the appended claims.

In the drawings—

Figure 1 is a side view of an overhead door installation in which the spring attaching means of the present invention is utilized;

Fig. 2 is an enlarged, fragmentary view partially in cross section for showing details of construction of the spring connections;

Fig. 3 is a similar view of the upper attaching means turned 90° from the position shown in Fig. 2;

Fig. 4 is a top view of the upper attaching means installed in the spring; and

Fig. 5 is a bottom view of the attaching means at the bottom end of the spring.

Referring to the drawings, there is shown in Fig. 1 a sufficient illustration of an overhead door assembly to illustrate a use of the present invention, this assembly being substantially the same as that shown in my prior Patent No. 2,045,100

2

issued June 23, 1936. In the over head door construction disclosed in Fig. 1, the door 10 is supported for operation so that, when it is moved from vertical closed position (as shown in the drawings) to an overhead horizontal position, the upper end of the door moves rearwardly while the lower end swings forwardly and upwardly and then rearwardly. To effect this movement, the door 10 is supported adjacent its lower end by a pair of swinging arms 11 (shown one), there being one arm 11 at each side of the door. As the constructions at opposite sides of the door are similar, the arrangement at only one side will be described, it being understood that a description of one will apply to either.

The arm 11 is pivotally mounted at its upper end at 12 on the bracket 13 which is attached to the door jamb (not shown) in any suitable manner. Carried by the opposite end of the arm 11 is a fulcrum piece 14 which, in turn, is pivotally supported on the lower end of the door 10 by a U-shaped bracket 15.

The upper end of the door 10 is provided with a roller bracket 20 which carries a suitable roller 21 which rides in a horizontal track 22 mounted adjacent the top of the door opening and extending rearwardly therefrom. As will be apparent, when the door is opened, the upper end is carried rearwardly on the track 22 by engagement of the roller 21 therewith while the lower end of the door is swung forwardly and upwardly at the end of the arm 11.

For the purpose of counterbalancing the door in order that it may be raised with as little effort as possible and in order to prevent the door from quickly dropping to closed position when it is released from overhead position, a tension spring 30 is provided adjacent each arm 11, each spring being interposed between the fulcrum piece 14 and the jamb bracket 13. The upper end of spring 30 is anchored to the bracket 13 at a point above the pivot 12 of the arm 11 by lever 31. As will be apparent, the springs 30 will become tensioned when the door is brought to a closed position. In general, in order to provide a sufficient counterbalancing force, particularly with very heavy doors, it is necessary to utilize very heavy springs. The type of spring illustrated is, of course, a conventional spiral type spring formed in any suitable manner such as from tempered heavy steel wire.

The present invention is particularly directed to the attaching means utilized for connecting the ends of the spring to the fulcrum piece 14

and the bracket 13, respectively. This device is best shown in detail in Figs. 2-5.

Referring to Figs. 2-5, the connecting means of the present invention comprises essentially a plate 40 which is of a particular construction and configuration permitting it to be readily and easily assembled with the spring and affording an improved and superior connection to the spring, all as described hereafter. It will be noted that the plate 40 is of greater length than the outside diameter of the spiral spring, but its width, particularly at the center portion 41, is smaller than the inside diameter of the spiral spring. The ends 42 and 43 are each slightly tapered as shown in Figs. 4 and 5.

The end portion 43 of plate 40 is arched or struck up to provide a channel-like seat 44 into which will be received a portion of one convolution of the spiral spring as illustrated particularly in Fig. 2 of the drawings. The seat 44 is offset from the plane of the plate 40 so that, when the seat 44 is engaged on a portion of one convolution of the spiral spring while the opposite end 42 extends between the portions of convolutions diametrically opposite therefrom, the center portion 41 remains substantially at right angles to the axis of the spring.

In the modification of the plate 40 utilized at the top of the spiral spring, as illustrated in greater detail in Figs. 3 and 4, the central portion 41 is sufficiently narrow to permit the plate 40 to extend through a U-shaped bracket 50. As illustrated in the drawings, the bracket 50 is provided with aligned openings 51 by means of which the bracket is pivotally mounted on the lever 31 which, in turn, is connected to the bracket 13. When assembled, the sides of the U-shaped bracket 50, by engaging the inner surfaces of the spring, effectively prevent sidewise displacement of the plate 40 and lock the attachment to the spring.

The insertion of the U-shaped bracket 50 and the plate 40 into position in the spring is an exceedingly simple operation. It is necessary only to open the spring at the proper place, as, for example, by means of a simple pneumatic device with two wedge-shaped jaws (not shown), whereupon the bracket 50 may be inserted into the end of the spring and the plate 40 may be dropped through the opening in the spring made by the pneumatic device and within the bracket 50. When the spring is released, the connection provided by the bracket 50 and the plate 40 is completed and disengagement thereof, particularly when the device is placed under tension, is impossible.

In the modification of the plate 40 utilized on the lower portion of the spring 30, the plate 40 is provided with a center hole 46 for receiving a threaded bushing 45. The threaded bushing 45 is adapted to receive an elongated threaded rod or bolt 60, whose lower end is connected to the fulcrum piece 14. By turning the bolt or rod 60, the plate 40 is moved toward or away from the fulcrum piece 14, whereby the tension on the spring 30 may be regulated.

In the last described modification, the center portion 41 is made somewhat larger than in the first described modification so as to more closely fit within the inside of the spring. Since the seat 44 is offset from the plane of portion 41, the latter is positioned so as to abut against the interior of the spring convolutions, which will prevent lateral displacement of the plate 40. As in the case of the modification previously de-

scribed, the insertion of the plate 40 is exceedingly simple. As explained above, it is necessary only to separate the spring in the desired place, whereupon the plate 40 may be readily dropped into place and is locked in position when the spring is released.

It will be apparent that either modification of the plate 40 may be connected to the spring at any desired place, that is, between any two adjacent convolutions, as desired. Because no adjustment of the attaching means is required in situ nor any attaching or locking operation need be carried out, it is unnecessary to resort to extended and expensive hand operations in order to install the spring. The result is that the attachment and installation of spiral springs may be carried out in less time and at extremely low cost with a minimum of required skill and training.

The attaching means is of simple design and may be rapidly fabricated in automatic operations. Despite the simplicity of the device, a foolproof connection is obtained which provides all of the required attributes of adjustability, ruggedness, and strength to insure satisfactory service over long periods of operation.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. A connector spring assembly comprising a spiral spring, a steel plate of greater length than the outer diameter of the spiral spring and having a center portion of lesser width than the inner diameter of the spring, one end only of the plate having a substantially semicircular offset arch to form a transverse bearing surface spaced from the plane of said center portion, said plate being disposed between convolutions of the spring to seat said bearing surface on a portion of one of the convolutions and with the opposite end of the plate extending outwardly beyond the opposite portion of the said one convolution, thereby placing the center portion of the plate substantially perpendicular to the axis of the spring within the convolution for preventing side slip, said central portion of the plate being provided with a threaded opening, and a threaded member engaging in said opening and extending outwardly in substantial alignment with the axis of the spring.

2. A connector spring assembly comprising a spiral spring, a steel plate of greater length than the outer diameter of the spiral spring and having a center portion of lesser width than the inner diameter of the spring, one end only of the plate having a substantially semicircular offset arch to form a transverse bearing surface spaced from the plane of said center portion, said plate being disposed between convolutions of the spring to seat said bearing surface on a portion of one of the convolutions and with the opposite end of the plate extending outwardly beyond the opposite portion of the said one convolution, thereby plac-

ing the center portion of the plate within the convolutions substantially perpendicular to the axis of the spring, and a generally U shaped bracket adapted to be inserted axially into the spring for receiving the said center portion of the plate.

3. A spring connector assembly comprising a spiral spring, a steel plate including a substantially flat central portion, a substantially flat one end portion and a substantially semicircular offset other end portion forming a transverse bearing surface spaced from the plane of said central and one end portions, said plate being disposed between convolutions of the spring to seat said bearing surface on a portion of one of the convolutions and with the opposite end of the plate extending outwardly beyond the opposite portion of the said one convolution, thereby placing the center portion of the plate substantially perpendicular to the axis of the spring within the con-

5

volution for preventing side slip, and fastening means carried by said central portion by which the assembly may be anchored to a selected object.
